UNITED STATES PATENT OFFICE.

THOMAS MIERSMA, OF MUSKEGON, MICHIGAN.

CURTAIN STRETCHER.

Application filed November 17, 1924. Serial No. 750,367.

To all whom it may concern:

Be it known that I, THOMAS MIERSMA, a citizen of the United States, residing at Muskegon, in the county of Muskegon and 5 State of Michigan, have invented certain new and useful Improvements in Curtain Stretchers, of which the following is a specification.

My invention relates to improvements in 10 curtain stretchers and drying frames, and its objects are: first, to provide a means whereby the frame may be readily adjusted for any size of curtains to be stretched and dried; second, to provide a means whereby 15 the frame may be easily and readily taken to pieces and stored away, and, third to provide a means whereby the long rails of the frame may be folded together for storing in small space, or may be extended and held 20 rigidly in extended position.

I attain these objects by the construction of parts shown in the accompanying drawing, in which Fig. 1 is a perspective of the frame assembled. Fig. 2 is a perspective of 25 one of the blocks used in the makeup of the ends of the frame, showing it made of two pieces of wood glued together. Fig. 3 is a perspective of a short piece of the side rail of the machine, and of one of the blocks used 30 in the makeup of the end rails, showing the manner of assembling them. Fig. 4 is a plan of one corner of the frame indicating how the parts may be assembled. Fig. 5 is a 35 plan of the two edges of the side rails showing the application of a hinge and a hasp for rendering said rails convertible as to length. Fig. 6 is a plan of the adjustable end of the end rail. Fig. 7 is a like view of the permanently connected end of said rail, 40 and Fig. 8 is an elevation of one of the blocks used in the make up of the end rail, shown as made of a single, solid block.

Similar reference numerals indicate similar parts throughout the several views in the 45 drawings.

In the construction of these frames I make use of two end rails made up of the long section 1 and several short sections or blocks 50 2, all of which have holes bored or formed through them, as indicated in Figs. 2 and 8. In Fig. 2 I have shown one of the short sections or blocks made in two pieces glued together upon the line 13, and with the holes 12 made square, while in Fig. 8 I have shown 55 the block or section made of one piece and with the holes 12 made round for the recep-

tion and free passage of the long supporting bolts 4. The bolts 4 are designed to pass through the parts 1 and 2 the whole length of the end rails and are secured in place in 60 the part 1 by means of securing pins 11, or other available device, so they cannot be slid longitudinally through this section of the rail. This is so that the end rails may be 65 securely connected with the side rails 3 by means of passing the bolts 4 into the slots 8 in said side rails and securing them firmly in place by means of the hand nuts or thumb or wing nuts 5. These side rails may be used interchangeably. That is, either of said 70 rails may be used as the permanently secured rail at the end of the end rails, or as the adjustable rail secured in the body of the end rails. It will be noted that these side 75 rails are provided with a number of the slots 8 for the reception of the bolts 4, so the end rails may be adjusted thereon to meet any length of curtain. The rails 3 are divided at the longitudinal center, as indicated at 10, and a hinge 6 is secured to one edge, by 80 means of which the two parts of the rails may be folded together, and upon the other edge of said rails is secured a hasp 7 consisting of a hook and staple, by means of 85 which the parts may be rendered rigid at the division line 10, as indicated in Fig. 1.

In the assembling of this frame the first action is to place the bolts 4 into the desired 90 grooves 8 to accommodate the desired length of curtain, and to secure them firmly in place by the firm placing of the nuts 5. The next action is to separate two of the sections 2 at a proper distance from the permanent rail to meet the desired width of curtain, then enter the adjustable rail 3 by passing 95 the proper slots 8 up over the bolts 4 and clamping the rail firmly in place between the two sections 2 of the rails 1-2 by screwing the nuts 5 firmly against the edge of the end section 2 of each end rail. 9 indicates 100 hooks for securing the curtains to the frame.

Having thus fully described my invention, what I claim as new in the art, is:

1. In a curtain stretcher frame, side rails having laterally disposed slots therein, end rails made up of a number of short longitudinally adjustable sections each section having holes therethrough longitudinally, bolts passed through said holes and arranged to pass into the slots in the side rails, and thumb nuts on said bolts, all arranged to clamp one end of the side rails firmly to the 110

end rails and the other side rail firmly between two sections of each of the end rails, and hooks thereon for securing the curtains in place upon the frame.

5. 2. In a curtain stretcher frame, side rails having laterally disposed slots formed in one side thereof, said side rails made in two pieces longitudinally and hinged together at their line of division, a hook and staple set 10 opposite the hinge in position to be connected and hold the said rails rigidly in extended position, end rails made up of a long section and several short sections, each of said sections having two holes through 15 them longitudinally, bolts passed through said holes, all so constructed that the bolts may be positioned in the slots in the side rails and the several rails clamped firmly together, and all so arranged that the sev-

eral rails may be changed in their relative 20 positions and adjusted to meet the length and width of any size of curtain.

3. In combination with a curtain stretching frame made up of a permanently secured side rail, and an adjustable side rail, having 25 laterally disposed slots therein, and end rails made up of a long section and several short sections having holes therethrough, bolts 30 passed through said holes and adapted to be passed into the slots in the side rails and to clamp the side rails and the end rails firmly together, and means for preventing the bolts from sliding in the long section of the end rails when clamping the end rails upon the 35 permanently located side rail of the frame.

Signed at Grand Rapids, Michigan, November 14, 1924.

THOMAS MIERSMA.
